DESIGN FOR A COMBINED MANICURIST'S TRAY AND LAMP

Alida di Nardo, Cleveland, and Betty D. Lieber,
Cleveland Heights, Ohio

Application June 7, 1938, Serial No. 77,638

Term of patent 3½ years

To all whom it may concern:

Be it known that we, Alida di Nardo and Betty D. Lieber, citizens of the United States and residents of Cleveland, and Cleveland Heights, county of Cuyahoga, and State of Ohio, have invented a new, original, and ornamental Design for a Combined Manicurist's Tray and Lamp, of which the following is a specification, reference being had to the accompanying drawing, forming a part thereof.

In said annexed drawing:

Fig. 1 is a front elevational view of the combined manicurist's tray and lamp showing our new design; Fig. 2 is a side elevational view of the same; Fig. 3 is a top plan view; Fig. 4 is a plan view taken substantially along line 4—4 of Fig. 2; and Fig. 5 is a sectional view taken substantially along line 5—5 of Fig. 4.

The combined manicurist's tray and lamp has bright, metallic, light reflecting surfaces.

We claim:

The ornamental design for a combined manicurist's tray and lamp, as shown and described.
